UNITED STATES PATENT OFFICE.

FRANCIS P. COFFIN, OF SCHENECTADY, NEW YORK, ASSIGNOR TO GENERAL ELECTRIC COMPANY, A CORPORATION OF NEW YORK.

VAPOR ELECTRIC DEVICE.

1,075,402.

Specification of Letters Patent. Patented Oct. 14, 1913.

Application filed January 25, 1913. Serial No. 744,059.

To all whom it may concern:

Be it known that I, FRANCIS P. COFFIN, a citizen of the United States, resident of Schenectady, county of Schenectady, State 5 of New York, have invented certain new and useful Improvements in Vapor Electric Devices, of which the following is a specification.

The present invention relates to mercury vapor devices and particularly to the construction of large, high powered vapor rectifiers having metal containers. One of the main problems in the operation of these high powered rectifiers is the maintenance 10 of steadiness in the arc. In devices as heretofore constructed the cathode spot is apt to temporarily jump to the metal wall of the cathode chamber, especially when mercury globules have condensed on the wall, 15 thus causing the arc to be temporarily extinguished, or as it is termed, causing "winking" of the arc.

In accordance with my invention the metal cathode chamber is insulated from the 20 main arc chamber, and is also provided with a refractory insulating ring or lining overlapping with said insulation for confining the arc and preventing it from injuring the insulation by its heating action and from 25 climbing up the metal surface.

The structural details of the cathode chamber of the rectifier are shown in the 30 sectional view in Figure 1 and the relation of the cathode to the other parts of the rectifier are shown respectively by the side and top view in Figs. 2 and 3.

As shown in Fig. 2 the rectifier consists of a main arc chamber 1 to which is joined a cathode chamber 2, insulated therefrom as 40 will be described. In the main arc chamber there are anodes 3 and 4 surrounded by shields 5 and 6 of suitable refractory material such as silica, alumina or the like. Two anodes have been indicated but of 45 course, any number of anodes may be used. The cathode chamber communicates with the main arc chamber by means of a throat 7 as clearly shown in Fig. 1. This throat is joined preferably by welding to the wall 8 50 of the main envelop and also to an annular disk of metal 9. For convenience of welding the part 9 is recessed near its juncture with its throat 7 to reduce the amount of metal. After the weld has been made a 55 threaded ring 10 is preferably driven into

this recess to which may be secured the lower or hanging section of the throat. To the metal cathode vessel is joined another annular disk or flange 11 through which pass a number of bolts 12, two of which are 60 shown. These bolts are insulated from the cathode container by a sleeve 13 of fiber or like material. Asbestos molded with a binder of a phenol-formaldehyde condensation product is suitable for this purpose. 65 The bolts are provided with nuts 14 at either end and spring washers 15.

Interposed between the cathode cup 2 and the flange 9 is an annular section of insulation 16. The particular insulation illustrated consists of a ring of porcelain upon each side of which bear pressure distributing plates 17 and 18. Aluminum washers are provided between the plates 17 and 18 and the adjoining metal wall of the container. As indicated washers of yielding material, such as asbestos and lead, or rubber, are used between the porcelain cylinder 16 and the plates 17 and 18. By tightening the nuts 14, a perfectly vacuum-tight 80 seal may be made. This asbestos may be impregnated with a cementing material so that when hardened the porcelain and the pressure distributing plates may be handled as one unit. 85

Lining the cathode pot 2 and extending beyond the insulating ring 16 is a refractory lining or cylinder 19 consisting of silica, alumina and similar refractory insulating material. It is a function of this 90 insulating lining to confine the active surface of the cathode upon which the cathode spot plays and thus to prevent wandering of the cathode spot up the side of the metal wall of the cathode pot. My experiments have 95 shown that unless such a barrier is provided a cathode spot will soon injure the insulation between the cathode chamber and the main arc chamber. The ring 19 also serves to protect the insulation from the direct 100 heating action of the arc. It is assisted in this heat shielding function by the lower hanging wall of the throat. I have found that if it is attempted to locate this insulation at some distance from the active part 105 of the cathode, and thus to prevent its overheating, globules are condensed on the intervening wall. The arc is very apt to jump to these globules of mercury causing unsteadiness of the arc and defeating the very 110

purpose for which the cathode was insulated. If desired the ring or wall 19 may be cemented into direct contact with the insulation 16 but this is not necessary. In 5 the drawing the ring 19 is shown as floating in the mercury, it being forced into contact with the plate 18 by its buoyancy.

The anodes are made vacuum-tight and insulated similarly to the cathode, as indicated in Fig. 2 by seals 20 and 21. The rectifier is started in operation by drawing 10 an arc between the cathode 22 and the rod 23 consisting of molybdenum or other metal. This may be done automatically by means of 15 a magnet 24 which draws up its plunger and lifts the rod 23 drawing the arc. The rod 23 is finally drawn up into a graphite sleeve 25. The arc is transferred to this 20 sleeve which acts as a sustaining electrode in a well known manner during the operation of the device. The graphite sleeve is attached to a metal tube 26, the lower end of which is indicated in Fig. 1 and to which the plunger mechanism is bolted. The main 25 chamber 1 of the rectifier is preferably maintained at the potential of the sustaining anode by electrically connecting it thereto.

A rectifier constructed as above will carry 30 loads of hundreds of kilowatts continuously.

What I claim as new and desire to secure by Letters Patent of the United States, is:—

1. In a vapor electric device, a main evacuated metal arc chamber, a mercury cathode, a metal chamber therefor, vacuum-tight insulation between said chambers, and a lining of refractory material for said cathode 35

chamber, said lining overlapping the insulation separating said chamber from the main 40 arc chamber.

2. In a vapor electric high powered rectifier, a main evacuated metal chamber, a mercury cathode, a metal chamber therefor opening into said main chamber, vacuum-tight insulation between said chambers, and a refractory insulating sleeve interposed 45 between said insulation and the active surface of the cathode.

3. A vapor electric device comprising 50 communicating evacuated metallic chambers, at least one anode in one of said chambers, and a mercury cathode in the adjoining chamber, a vacuum-tight insulating seal between said chambers at a point removed 55 from said cathode, a barrier of insulating material lining the cathode chamber overlapping with said seal and inclosing the active portion of the cathode and a wall of metal confining the arc. 60

4. In a vapor electric device, a main evacuated metal container, a communicating metal chamber, an easily vaporizable cathode therein, vacuum-tight insulation between said chambers, a sleeve of refractory material confining the active portion of 65 said cathode, and arc-directing means projecting from said main chamber, and projecting into said sleeve.

In witness whereof, I have hereunto set 70 my hand this 23rd day of January 1913.

FRANCIS P. COFFIN.
